(57) **CLAIM**

(22) Filed: **Jul. 24, 2001**

The ornamental design for a knob for raising the cover of a cooking vessel, as shown and described.

(30) **Foreign Application Priority Data**

DESCRIPTION

Jan. 24, 2001 (FR) 01 0435

FIG. 1 is a top and side perspective view of a knob for raising the cover of a cooking vessel, showing my new design;

(51) LOC (7) Cl. **07-02**

FIG. 2 is a side perspective view thereof, the side opposite that shown in FIG. 2 being the mirror image thereof; FIG. 3 is a side elevational view thereof from the left of FIG. 2; and,

(52) U.S. Cl. **D7/393**

FIG. 4 is a top plan view thereof.

(58) **Field of Search** D7/393, 354-361; D8/300, 307, 310, 312; 220/752, 753, 755, 912, 573.1; 16/110.1, 441, 433

The under side is hidden in use and its appearance forms no part of the claimed design.
